UNITED STATES PATENT OFFICE.

CARL H. BISSELL, OF SYRACUSE, NEW YORK, ASSIGNEE TO CROUSE-HINDS COMPANY,
OF SYRACUSE, NEW YORK, A CORPORATION OF NEW YORK.

MOTOR-STARTING SWITCH.

1,116,552.

Specification of Letters Patent.

Patented Nov. 10, 1914.

Application filed May 21, 1913. Serial No. 768,932.

To all whom it may concern:

Be it known that I, CARL H. BISSELL, of Syracuse, in the county of Onondaga and State of New York, have invented a certain new and useful Motor-Starting Switch, of which the following is a specification.

This invention relates to switches and particularly motor starting switches and has for its object means for controlling the operation of the shiftable switch member and the invention consists in the combinations and constructions hereinafter set forth and claimed.

In describing this invention, reference is had to the accompanying drawings in which like characters designate corresponding parts in all of the views.

Figure 1 is a side elevation of a switch embodying my invention, the casing for said switch being also shown in section. Fig. 2 is a plan, partly in section, of parts seen in Fig. 1, the cap of the case and parts carried thereby being removed. Fig. 3 is an end elevation of parts seen in Fig. 1, the case being in section. Fig. 4 is a fragmentary, longitudinal, sectional view illustrating the position of the shiftable switch member and coacting parts when the switch member is thrown into position to start the motor. Figs. 5 and 6 are fragmentary views illustrating the operation of the means for controlling the throwing of the switch.

1 is the base of the switch having two or two sets of terminals or contacts 2 and 3.

4 is the movable member of the switch having arms or knives 5, 6 movable respectively into engagement with the terminals or contacts 2, 3.

The base 1, as here shown, is suitably mounted in a box or case 7 having means, as internally threaded nipples 8, for connection with conduits inclosing the service wires, and terminals for binding devices 10, 11 are mounted on the base for connection with the service wires.

The terminals 10 are connected by conductors 12 in circuit with the movable switch member 4 and the terminals 11 are connected to the contacts 3 by conductors including fuses 13. The terminals 11 are also connected to the terminals 2 by conductors 14. The movable switch member 4 oscillates forwardly and rearwardly about the axis of the shaft 15 supported by the base 1 midway between the terminals 2, 3, and the arms 5, 6

extend in a radial direction from the shaft, the arms 5 moving into contact with one terminal or set of terminals as 2 when the movable switch member is shifted in one direction as forwardly, that is upwardly in Fig. 2, and the arms 6 moving into contact with the second terminal or set of terminals as 3 when the switch member 4 is moved in a second direction or rearwardly, that is downwardly in Fig. 2, the movable switch member being normally in its neutral position in which both arms 5, 6 are out of engagement with the terminals or contacts 2, 3. The movement of the switch member forwardly from its neutral position; that is upwardly in Fig. 1 is against the action of a returning spring 16. There are here shown three terminals or contacts 2 or 3 in each set and the switch member is therefore provided with three arms or knives 5 or 6. In operation the switch is shifted from its neutral position until the knives 5 engage the terminals or contacts 2 whereupon the current passes from the feed wires to the terminals 10, conductors 12, knives or switch arms 5 terminals 2, conductor 14 and terminals 11. After the motor has been started; that is has developed its normal speed, the movable switch member 4 is moved from its position shown in Fig. 4 toward and beyond its neutral position to carry the arms or knives 6 into engagement with the contacts or terminals 3, whereupon the current passes from the service wires to the terminals 10, conductors 12, switch arms 6, terminals 3, fuses 13 and the terminals 11.

Mechanism or means is provided for preventing movement of the switch member 4 from its neutral position into a position in which the knives or arms 6 engage the terminals 3, for the purpose of avoiding burning out of the fuses 13 connected to said terminals 3, by the excessive rush of current which occurs when the motor is started, said mechanism being automatically shiftable out of operative position after the movable switch member 4 has been moved forwardly to carry the knives 5 into complete engagement with the terminals 2 and permitted to be acted upon by the returning spring 16. As here shown, said mechanism includes an element arranged in the path of movement of the shank 4^a of the switch member 4 to prevent movement of said member rearwardly to carry the knives 6

2
into engagement with the terminals 3; said element being automatically movable by the shank 4^a out of the path of the shank after completing its forward movement; and 5 usually said mechanism includes a detent 17 and means for moving the detent out of position including an element 18 projecting into the path of the shank 4^a of the member 4 to be engaged thereby when the switch 10 member is moved forwardly from its neutral position, to engage the knives 5 with the contacts 2, the element 18 being designed to ratchet from one side of the shank to the other side thereof as the knives 5 complete 15 engagement with the terminals 2 so that said element 18 is in position to be carried by the shank 4^a of the member 4 into engagement with the detent 17 and move the detent out of operative position when 20 the switch member 4 is being moved in a retrograde direction by the spring 16 to carry the knives 6 into the contact or terminals 3.

As here shown, the shank 4^a of the movable switch member 4 projects through a slot 19 in a cap 20 of a box 7, and the detent 17 and element 18 are pivoted to a bearing 21 depending from the inner face of said cap 20 at one side of the slot, the parts 17 30 and 18 having a common pivot. The detent 17 is angular in form and pivoted at its angle, one arm thereof carrying a hook shaped shoulder 22 normally arranged in the path of the shank 4^a of the switch member 4 and the other arm thereof being connected by a spring 23 to a lug 24 depending from the inner face of the cap 20, the spring 23 serving to normally hold the detent 17 in its operative position and to return the same to its operative position.

The element 18 is an arm or lever projecting across the slot 19 and into the path of movement of the shank 4^a of the switch member 4, and the lever or arm is provided with a shoulder 18^a at its end, which shoulder projects into the plane of the detent 17 in order to engage said detent. Said lever 18 is held in, and returned to, its normal position by a spring 25 connected to the rear end of the lever 18 and to the end of the rear arm of the detent 17. The lever 18 is of less length than the throw of the coacting portion of 4^a of the shank 4 forwardly, and is long enough to remain in contact with the shank 4^a until the switch member completes its movement in the starting or forward direction; that is, until the knives 5 engage the contacts 2 or the knives 6 engage the contact 3 whereupon said lever 60 18 ratchets past the shank 4^a of the member 4 to its normal position.

In operation, the switch member is normally in its neutral position with its shank 4^a interposed between the detent 17 and the 65 lever 18 as seen in Figs. 1, 3, 5 and 6.

Upon the forward movement of the switch member the shank thereof engages the lever 18 moving the same on its pivot 21 until the knives 5 complete their engagement with the contact 2 whereupon the lever 18 ratchets or is moved by its spring 25 as illustrated in dotted lines, Fig. 5, the spring 25 moving the lever 18 to its normal position. The movement of the lever forwardly is against the action of the returning spring 75 16 and the operator holds the switch member with the knives 5 engaging with the contacts 2 until the motor develops approximately full speed, whereupon the operator releases the switch member 4 and said 80 switch member is moved rearwardly by the spring 16, the shank thereof engaging the lever 18 and moving the same until the shoulder 18^a thereof engages the detent 17, the lever 18 thus pushing the detent 17 out 85 of the path of the switch member 4 as shown in Fig. 6. After the switch has been moved rearwardly, the parts 17 and 18 are returned by their springs 23 and 25 to their normal 90 positions. The detent 17 is provided with an inclined ratchet surface 26 at its rear end arranged to engage the shank of the member 4 and cause the detent 17 to ratchet and permit the switch member 4 to move past the same to its neutral position. 95

What I claim is:—

1. The combination of a switch including a member shiftable from a neutral position in one direction to make contact with one terminal and in a second direction to make contact with a second terminal, means for normally preventing the movement of the switch member from its neutral position into engagement with the second terminal, and means operable by the switch member for 100 moving and holding the former means out of operative position, after the switch member has been shifted into engagement with the first terminal and returned beyond its neutral position into engagement with the 105 second terminal, substantially as and for the purpose specified.

2. The combination of a switch including a member shiftable from a neutral position in one direction to make contact with one terminal and in a second direction to make contact with a second terminal, means normally arranged to prevent movement of the switch member from its neutral position into engagement with the second terminal, and means arranged in the path of the switch member when moving into the engagement with the first terminal and operable to ratchet by the switch member as the switch member completes its engagement with the first terminal, into position to be moved by the switch member into engagement with the former means to shift the same out of the path of the switch member during the return movement of the switch 110 115 120 125 130 135

beyond its neutral position into engagement with the second terminal, substantially as and for the purpose set forth.

3. The combination of a switch including a member shiftable from a neutral position in one direction to make contact with one terminal, and in a second direction to make contact with a second terminal, means normally arranged in the path of movement of the switch member to prevent shifting of the same from its neutral position in the second direction, and means normally arranged in the path of the switch member when the same is moved in the first direction, the latter means having a ratcheting action from either side of switch member to the other, after said member moves in either direction and being movable into engagement with the former means to shift the same out of the path of the switch member when said member is moved in the second direction after engaging the first terminal, substantially as and for the purpose described.
4. The combination of a switch including a member shiftable from a neutral position in one direction to make contact with one terminal and in a second direction to make contact with a second terminal, a detent normally arranged in the path of the switch member for normally preventing movement of the said member from its neutral position into engagement with the second terminal, and means movable by the switch member into engagement with the detent to move the same out of operative position, after the switch member has been moved into and out of contact with the first terminal and toward and beyond its neutral position in the second direction to engage the second terminal, substantially as and for the purpose set forth.

5. The combination of a switch including a movable member shiftable from a neutral position in one direction to make contact with one terminal and in a second direction to make contact with a second terminal, mechanism normally arranged to prevent movement of the switch member from its neutral position in the second direction, said mechanism including an element projecting into the path of movement of the switch member, said element having less movement than the throw of the coacting portion of the said member in either direction and being arranged to ratchet from the advance to the opposite side thereof as the switch member completes its contact with the first terminal and into position to be pushed out of the path of said member during movement of said member beyond its neutral position in the second direction, substantially as and for the purpose described.

6. The combination of a switch member including a member shiftable from a neutral

position in one direction to make contact with one terminal and in a second direction to make contact with a second terminal, mechanism normally arranged to prevent movement of the switch member from its neutral position in the second direction, including a detent projecting into the path of the movement of the switch member when the same is moved in the first direction from its neutral position, and having a shoulder for engaging said detent during movement of the arm in the second direction after the switch member engages the first terminal, said arm having less movement than the throw of the switch member in either direction in order to ratchet by the switch member substantially as and for the purpose specified.

7. The combination of a switch including a member shiftable from a neutral position in one direction to make contact with one terminal and in a second direction to make contact with another terminal, a detent normally arranged to prevent movement of the switch in the second direction from its neutral position and a shifter arm for the detent arranged in the path of the movement of the switch member when the same is moved in the first direction from its neutral position, and the shifter arm being arranged to ratchet past the switch member as said member completes its movement in the first direction and to engage and shift the detent out of the operative position during the movement of said member in the second direction, and to ratchet to its normal position after the switch member clears the detent, substantially as and for the purpose set forth.

8. The combination of a switch including a member shiftable from a neutral position in one direction to make contact with one terminal and in a second direction to make contact with another terminal, a detent normally arranged to prevent movement of the switch in the second direction from its neutral position, and a shifter arm for the detent arranged in the path of the movement of the switch member when the same is moved in the first direction from its neutral position, and the shifter arm being arranged to ratchet past the switch member as said member completes its movement in the first direction and to engage and shift the detent out of operative position during the movement of said member in the second direction, and to ratchet past said member after shifting the detent, the detent being provided with a ratchet surface arranged to engage the switch member during movement thereof out of engagement with the second terminal and permitting the switch member to ratchet past the detent to its neutral position, substantially as and for the purpose described.

9. The combination of a switch including

a member shiftable from a neutral position forwardly and rearwardly a pivoted detent projecting into the path of said member for normally preventing movement of the same from its neutral position in a rearward direction, and an arm pivoted at one side of the path of said member and normally projecting across said path, said member normally extending between the detent and the arms, the arm having means for engaging the detent and shifting the same out of operative position during the rearward movement of said arm, and the arm being of shorter length than the throw of said member in either direction from its neutral position so as to ratchet past said member, substantially as and for the purpose specified.

10. The combination of a switch including a member shiftable from a neutral position forwardly and rearwardly, a pivoted detent projecting in the path of the said member for normally preventing movement of the same from its neutral position in a rearward direction, and an arm pivoted at one side of the path of the said member and normally projecting across said path, said member normally extending between the detent and the arm, the arm having means for engaging the detent and shifting the same out of operative position during the rearward movement of said arm and the arm being of shorter length than the throw of said member in either direction from neutral position so as to ratchet past said member, the detent

and the arm being mounted on a common pivot on one side of the path of movement of the switch, substantially as and for the purpose set forth. 35

11. The combination of a switch including a member shiftable from a neutral position forwardly and rearwardly, a pivoted detent projecting into the path of said member for normally preventing movement of the same from its neutral position in a rearward direction and an arm pivoted at one side of the path of the switch member and normally projecting across said path, the arm having means for engaging the detent and shifting the same out of operative position during the rearward movement of said arm and the arm being of shorter length than the throw of the said member in either direction from the neutral position so as to ratchet past the said member, and the detent having a ratchet surface at its rear end for engaging the said arm and permitting the same to ratchet past the detent when the said member is moving from its rear to its neutral position, substantially as and for the purpose described. 40 45 50 55

In testimony whereof, I have hereunto signed my name in the presence of two attesting witnesses, at Syracuse, county of Onondaga, in the State of New York, this 1st day of May, 1913. 60

CARL H. BISSELL.
